[57] CLAIM

The ornamental design for a cap molding for butt joints,
as shown and described.

DESCRIPTION

FIG. 1 is a perspective view of a cap molding for butt joints, showing my new design;
FIG. 2 is a top-plan view thereof;
FIG. 3 is a bottom-plan view thereof;
FIG. 4 is a front-elevational view thereof;
FIG. 5 is a rear-elevational view thereof; and
FIG. 6 is an enlarged cross-sectional view taken along
line 6—6 of FIG. 4.
